Raphael S. Green,

UNITED STATES PATENT OFFICE

RAPHAEL S. GREEN, OF CHICAGO, ILLINOIS.

WORK-HOLDER FOR SHARPENING BLADES.

1,200,420.

Specification of Letters Patent.

Patented Oct. 3, 1916.

Application filed April 12, 1915. Serial No. 20,763.

To all whom it may concern:

Be it known that I, RAPHAEL S. GREEN, a citizen of the United States, residing at Chicago, in the county of Cook and State 5 of Illinois, have invented certain new and useful Improvements in Work-Holders for Sharpening Blades, of which the following is a description, reference being had to the accompanying drawings, forming a part of 10 this specification, in which corresponding numerals of reference in the different figures indicate like parts.

My invention relates to work-holders adapted for use with machines for sharpening razor-blades and similar articles, which machines are so constructed as to 15 actuate a work-holder to alternately present opposite sides of the blade to be sharpened to opposed grinding or honing surfaces and at the same time cause said 20 holders to be moved laterally until the sharpening operation is completed.

The holders are intended to be detachable and any predetermined number may be 25 employed within the limits of the capacity of the machine. I have found in practice that holders of the type employed are liable to vary more or less in construction so that when a number are used at the same 30 time upon a given machine, set to a given adjustment, uniformity of results are not obtainable.

The object of my invention is to overcome 35 this difficulty by constructing a holder which may be so adjusted independently of its fellows, as to enable it to be used upon the same machine with others and with like accuracy as to results, all of 40 which is hereinafter more particularly described and definitely pointed out in the claims:

In the drawings: Figure 1, is a plan view of a machine showing a plurality of work-holders mounted thereon, Fig. 2, is a 45 section taken upon the line 2—2, Fig. 1, viewed in the direction of the arrow there shown, Fig. 3, is a side elevation of a work-holder embodying the features of my invention, a portion of the same being shown in 50 vertical longitudinal section, said holder being shown as it would appear when mounted upon the feed-screw and eccentric shaft, Fig. 4, is a plan view in detail of a portion of a work-holder showing means 55 for axial adjustment, and Fig. 5, is a sectional view taken upon the line 5—5, Fig. 4.

Referring to the drawings, 1, indicates the frame of a grinding machine having opposing rollers 2, 3, arranged to be rotated in opposite directions by means of 60 pulleys 4, 5, connected with a suitable source of power. Located in a plane midway between the faces of the sharpening rollers and parallel therewith, is a feed-screw 6, which is journaled in the frame 65 and provided with a driving pulley 7, upon one of its ends. Journaled in the frame, in the plane of the feed-screw 6, that is, midway between the opposing faces of the sharpening rollers 2 and 3, is an eccentric 70 shaft 8, having an eccentric portion 9, formed thereon between said bearings and corresponding substantially in length to that of the sharpening rollers. Said shaft is provided with a driving pulley 10. 75

A work-holder, generally designated by 11, is provided with a main body portion 12, to which is jointedly connected at 13, a hinged member 14, intended to be detachably connected therewith by means of a 80 locking member, the body 15, of which is journaled in a bore in the part 12 and provided with a locking finger 16, arranged to engage the free end of the part 14 and hold it in place. The part is adapted to be operated by means of a thumb-nut 17. A bore having an internal screw-thread, is formed in the two parts 12, and 14, being 85 equally divided between them for the reception of the feed-screw 6. The parts 12, 90 and 14, are cut away as shown at 18, and 19, respectively, to form an elongated opening between them for the reception of the eccentric shaft 9. A sheet-metal plate or tongue 20, preferably of spring steel, has 95 its forward end rigidly secured in the part 12, as shown at 21, while a like tongue 22, is secured in the same manner in a suitable notch formed at 23 in the member 14. Said springs tend to separate from each other so 100 as to bear normally against the inner faces of the parts 12 and 14. Opposing adjusting screws 24, and 25, are tapped into the parts 12, and 14, respectively in position to engage the free ends of said springs, which 105 later serve as bearing faces for the eccentric shaft 9. The purpose of said adjustment will be described later.

Tapped axially into the forward part of the member 12, is a threaded stem 26, which 110 is adapted to be locked in place, when adjusted, by means of a lock-nut 27. A sleeve

28, is loosely mounted upon said stem and is held in place by means of a pin 29, better shown in Figs. 4 and 5, which is passed through a bore in said stem. Elongated slots 5 30, 30, are formed in said sleeve to provide for a limited play or oscillation of the sleeve. A flat spring shank 31, is rigidly attached to the head of the sleeve to which, in turn, is secured flat spring clamping members 32, 10 having a clamping nut 33, of any well known construction for enabling the work to be clamped between them.

The operation of the holder, in conjunction with the machine in which it is adapted 15 to be used, is as follows: The razor blade, or other article, to be sharpened is first clamped between the jaws or holding members 32; the thumb-nut 17 is turned to release the part 14, which enables the holder 20 to be placed in an operative position upon the feed-screw 6 and eccentric shaft 9, as shown in Figs. 1 and 2. The rear end of the holder is caused to vibrate up and down by the rotation of the eccentric shaft there- 25 by alternately bringing the article to be sharpened into contact with the opposed sharpening rollers which are driven in opposite directions. If the threaded bore in the holder which engages the feeding shaft 30 is out of true, the rotation of the sleeve 28, upon the stem 26, will permit the blade as it is pressed against the sharpening surfaces, to assume true parallelism therewith and thus sharpen the article evenly from end to 35 end. In order, however, to insure uniform pressure against the opposing rollers, it is essential that the vibratory action of the eccentric shaft should cause the throw of the tool to be uniform with respect to the 40 plane between the opposing forces of the rollers. This may be accomplished with the utmost accuracy by means of the spring plates 20 and 22 and the adjusting nuts 24 and 25. Should, for example, a blade when 45 ground indicate an excessive pressure against the lower roll, an outward turn of the screw 24, and a corresponding inward turn of the screw 25, would tend to correct the difficulty. When all of the holders are 50 adjusted for a given machine, they will need no further attention as an adjustment of a given set of holders may be made once for all except to take up wear upon the eccentric shaft and adjusting plates, which, with 55 ordinary care, would be inappreciable. My improvement enables any predetermined number of work-holders to be accurately adjusted to a given machine.

Having thus described my invention, I 60 claim:

1. A work-holder of the class described, comprising, in combination, a body portion having an internally threaded transverse

bore therein for engagement with a feed-screw for moving said holder laterally, ad- 65 justable substantially parallel members se- cured in an elongated opening in said body to form opposing bearing surfaces for a rev- 70 oluble eccentric shaft to vibrate said holder upon said feed screw as a pivot, means for adjusting said members in different planes with respect to the longitudinal axis of said holder and a work-holding clamp mounted upon the end of said holder.

2. A work-holder of the class described 75 comprising, in combination a body portion consisting of jointedly connected, separable elements, having an internally threaded transverse bore and an elongated opening therein, a counterpart portion of each of 80 which is formed in said separable elements to provide for its connection with and re- 85 moval from a feed-screw and eccentric shaft in a machine for utilizing the same, adjust- 90 able members located in each of said coun- 95 terpart members to form opposing bearing members for a rotary eccentric shaft, means for adjusting said bearing members in dif- 100 ferent planes parallel with the longitudinal axis of said holder and a work-holding clamp mounted upon the end of said holder.

3. The combination with a vibratory work- 105 holder of the class described, to be vibrated upon a transverse pivotal axis, of a work- 110 holding clamp upon one end thereof and ad- 115 justable bearing members mounted in the body of said holder, said members having bearing surfaces arranged upon opposite sides of and parallel to the longitudinal axis of said holder, and means for moving said members to or from said longitudinal axis while maintaining substantial parallelism therewith.

4. The combination with a vibratory work- 105 holder of the class described to be vibrated upon a transverse pivotal axis, of a work- 110 holding clamp upon one end thereof mount- 115 ed to have axial movement thereon upon the longitudinal axis of said holder, and ad- 120 justable bearing members mounted in the body of said holder said members having bearing surfaces arranged upon opposite sides of and parallel to said longitudinal axis and means for moving said members to and from said longitudinal axis to adjust 125 the throw of said work-holding clamp to conform to predetermined opposite limits.

In testimony whereof, I have signed this specification in the presence of two sub- 130 scribing witnesses, this 31st day of March 1915.

RAPHAEL S. GREEN.
